AUGUSTIN J. CHEVRETTE, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS

TRANSFER AND FEELER CONTROL MECHANISM FOR SHUTTLE-CHANGING LOOMS

Application filed March 2, 1928. Serial No. 258,557.

This invention relates to shuttle changing looms of the general type shown in my prior application, Serial No. 196,378, filed June 3, 1927.

5 In the operation of the loom therein shown, the shuttle change occurred one pick after indication of weft exhaustion, which was found to provide a very limited period in which to affect the shuttle change.

10 It is the general object of my invention to provide mechanism by which the shuttle change will be delayed after indication, so that the transfer will take place on the third pick after indication instead of on the first 15 pick. A further object is to provide means for disabling the weft detector or feeler on the first return of the shuttle to the detecting side of the loom, after the indication of weft exhaustion.

20 My invention further relates to arrangements and combinations of parts which will be hereinafter described and more particularly pointed out in the appended claims.

The preferred form of the invention is 25 shown in the drawings in which

Fig. 1 is a partial side elevation of a loom embodying my invention, certain parts being shown in section;

Fig. 2 is a partial plan view, looking in the 30 direction of the arrow 2 in Fig. 1;

Fig. 3 is a detail sectional elevation, taken along the line 3—3 in Fig. 1;

Fig. 4 is a detail plan view, looking in the direction of the arrow 4 in Fig. 1;

35 Fig. 5 is a partial front elevation, looking in the direction of the arrow 5 in Fig. 1;

Fig. 6 is a partial side elevation at the right hand or weft detecting end of the loom;

Fig. 7 is a plan view of the parts shown 40 in Fig. 6;

Fig. 8 is a partial sectional rear elevation, taken along the line 8—8 in Fig. 6;

Fig. 9 is a side elevation of certain parts, looking in the direction of the arrow 9 in 45 Fig. 8; and

Fig. 10 is a diagrammatic representation of the successive positions of the shuttles during a shuttle change.

Referring particularly to Figs. 1 to 4, I 50 have shown parts of a shuttle changing loom

of the general type shown in my prior application above referred to, said parts comprising a loom frame 20, supporting a shuttle holder or magazine 21 in fixed position above the path of movement of a lay 22. A drop box frame 23 is mounted for vertical movement in the lay 22 and comprises an upper or regular shuttle box above the lateral projection 24 and a lower or auxiliary shuttle box below the projection 24. A binder 25 is 55 mounted in fixed vertical position and cooperates with the shuttle opposite thereto, whether it is located in the upper or lower box. A shuttle receiver 26 is mounted adjacent the forward position of the lay and 60 is adapted to receive the ejected shuttles. 65

When a shuttle change is indicated the drop boxes are elevated so that the regular box assumes a raised position in which it is adapted to receive a fresh shuttle from the magazine 76 21, while the lower or auxiliary box is positioned at the level of the lay to receive the exhausted running shuttle. As soon as the exhausted shuttle is thus received the boxes are lowered, releasing the exhausted shuttle 75 to the receiver 26 and placing the fresh shuttle in running position where it may be engaged by a picker actuated by the usual picker stick 27.

The drop boxes are mounted on a lifter rod 80 28 adapted to be moved vertically on the lay 22 and having a give-way connection 29 to a lifter lever 30, pivoted at 31 on the loom frame 20. An actuating lever 32 is also mounted to swing about the pivot 31 and is provided 85 with a roll 33 engaging a cam 34 on the regular bottom or cam shaft 35 of the loom.

A latch 36 (Fig. 2) is pivoted at 37 on the lever 32 and is normally held outward by a spring 38. An arm 39 projects downward 90 from the latch 36 and is connected by a spring 40 and chain or cord 41, bellcrank 42 (Fig. 1) and link or chain 43 to an arm 44 on a rock shaft 45. A spring 46 is provided to hold the lever 32 in engagement with its cam 34. 95

When the spring 40 is tensioned by the connections above described, the latch 36 is held yieldingly against the face of the lever 30 until the latch is moved below the lever, whereupon the latch is swung yieldingly in- 100

ward under the lever, in position to engage the lever 30 upon the next upward movement of the actuating lever 32 and latch 36.

The parts thus far described are in general similar to those shown in my prior application, except for the addition of the spring 40 and its connections.

Weft indicating mechanism is provided at the opposite side of the loom as indicated in Figs. 6 to 9. For this purpose I provide a detecting member or rod 54 slidably mounted in a support 55. When the detecting member 54 is moved forward for engagement by a full bobbin, it engages a depending arm 56 (Fig. 8) on a member 560 mounted on a stud 561 fixed in a lever 562. The member 560 is provided with a depending latch 57, and the lever 562 is pivoted at 58 on a fixed bracket 59. The outer end of the lever 562 is connected by a link 60 to an arm 61 secured to the right hand end of the rock shaft 45 previously described.

An actuating rod 62 is slidably mounted in a fixed bearing 63 and has its lower end connected to a cam lever 64 pivoted at 65 and having a cam roll 66 engaged by a path cam 67, also on the bottom shaft 35. The latch 57 is provided with a weight 68 (Figs. 6 and 7) which moves the latch to position for engagement by the notched upper end of the actuating rod 62, as indicated in full lines in Fig. 9, whenever the actuating rod is lowered.

If the weft detector 54 is then pushed forward by engagement with a full bobbin, the latch 57 is moved forward out of the path of the rising actuator 62, as indicated in dotted lines in Fig. 9. When the supply of weft becomes substantially exhausted, however, the detector 54 remains in rearward position and the latch is engaged by the upwardly moving actuator, causing the shaft 45 to be rocked and thus communicating movement to the control latch 36 for the drop box mechanism.

The cam 67 (Fig. 6) is so designed that the actuating rod 62 is normally elevated but is quickly lowered and immediately raised once in each revolution of the shaft 35, corresponding to two revolutions of the crank-shaft and to two beats of the lay. Consequently, if the latch 57 is engaged by the actuator, the latch 57 will be held raised for a considerable period, during which time the connections through the rock shaft 45 and bell crank 42 will hold the spring 40 (Fig. 3) under tension, so that the latch 36 will move to operative position under the lever 30 when the lever 32 is lowered.

The cam 34 is so designed and so positioned in relation to the cam 67 that the latch 36 cannot move to operative position immediately upon indication of weft exhaustion, but such movement will be delayed until the substantially exhausted shuttle has been picked from the drop box or magazine side of the loom. The latch 36 will then become operative, rais-

ing the drop boxes before the exhausted shuttle returns. By thus delaying the operation of the shuttle changing mechanism, it becomes unnecessary for the boxes to operate at the high speed previously required, the shuttle change operation is rendered more certain, and there is less liability of injury to the mechanism.

It is desirable to render the weft detector 54 inoperative during the intervening return flight of the exhausted shuttle to the detecting side of the loom before the shuttle change takes place. For this purpose, I provide a lever 70 (Figs. 1 and 4) pivoted at 71 on the loom frame 20 and having a pin 72 extending below the lifter lever 30. A spring 74 holds the pin yieldingly against the under side of the lever. A link 75 connects the lever 70 to an offset or crank portion 76 (Figs. 1 and 5) at the end of a cross rod 77, mounted in bearings 78 on the front of the loom. At the detecting side of the loom, the rod 77 is bent rearward and upward as indicated at 80 (Figs. 6 to 9) and is provided at its upper end with a stud 81 positioned to engage the latch 57. When the rock shaft 77 is moved angularly by its connections from the lever 70, the stud 81 is moved forward, swinging the latch 57 out of the path of the actuator 62 and thus holding the detecting mechanism inoperative regardless of the position of the detector 54.

Having thus described my invention and the details of construction thereof, the novel method of operation will be apparent by reference to the diagrams shown in Fig. 10. The numerals I, II, III, IV and V indicate successive picks in the operation of the loom and the lines 90 and 91 indicate the bottoms of the regular and auxiliary shuttle boxes, the line 92 indicating the shuttle race.

Let it be assumed that the shuttle S is indicated as substantially exhausted on the pick bearing the numeral I, the drop boxes being in normal position. On the next pick, indicated by the numeral II, the shuttle S is at the magazine side of the loom but in the upper or regular box and the boxes are still in their normal or lowered position.

At the beginning of the third beat, indicated at III^a, the shuttle S has started its return flight to the detector side of the loom and the drop boxes are about to begin their upward movement. The position of the parts at the end of the third beat is indicated in the sketch marked III^b, the shuttle S being again at the detecting side of the loom, the boxes being raised and the new shuttle S' being positioned in the upper box 90. It is at this point that the lifting of the boxes disables the detecting mechanism while the shuttle S is at the detecting side of the loom.

During the fourth beat the shuttle S returns to the drop box side of the loom and is received in the lower or auxiliary box 91, the new shuttle S' being at the same time

positioned in the raised regular box 90. The boxes are then lowered to the successive positions indicated at IV^b and IV^c until the new shuttle S' is in normal running position and the exhausted shuttle S is in lowered position and ready to be discharged.

On the fifth beat, the new shuttle S' travels to the detecting side of the loom, the parts then being in the same position as on the 10 first beat and the detector being released for further indication.

By the provision of delay in the shuttle change I make possible a more easy movement of the mechanism, and by connecting 15 the drop boxes to the control latch of the detecting mechanism I prevent effective operation of the detector during the intervening return flight of the exhausted shuttle.

Having thus described my invention and 20 the advantages thereof, I do not wish to be limited to the details herein disclosed otherwise than as set forth in the claims, but what I claim is:—

1. In a shuttle changing loom, weft detecting mechanism at one side of the loom, shuttle changing mechanism at the other side of the loom, and separate actuating cams for said two mechanisms, said cams being relatively positioned to delay the shuttle change 30 until after the second flight of the shuttle to the shuttle changing side of the loom.

2. In a shuttle changing loom, weft detecting mechanism at one side of the loom, shuttle changing mechanism at the other side 35 of the loom, and separate actuating cams for said two mechanisms, one of said cams being designed to hold an indication of weft exhaustion until after the shuttle begins a return flight to the detecting side of the loom.

40 3. In a shuttle changing loom, weft detecting mechanism at one side of the loom, shuttle changing mechanism at the other side of the loom, and control connections between said detecting mechanism and said shuttle changing mechanism, said connections including a box lifting lever, a latch to raise said lever, means to move said latch to engaging position relative to said lever, and means controlled by said detecting mechanism 45 for moving said latch under said lever, said means including a spring adapted to hold said latch under tension until said latch is free to move under said lever.

55 4. In a shuttle changing loom, weft detecting mechanism at one side of the loom effective to detect approaching weft exhaustion, shuttle changing mechanism at the other side of the loom including drop boxes 60 and box lifting devices, a connecting member controlled by said detecting mechanism and normally positioned to render said shuttle changing mechanism operative and a connection from said box lifting devices to said 65 connecting member effective to render said

connecting member inoperative when said drop boxes are raised.

5. In a shuttle changing loom, an actuating member having a regularly repeating movement, a latch normally positioned for engagement by said member, shuttle changing mechanism controlled thereby, a detector effective to move said latch to inoperative position when sufficient weft is present in the running shuttle, and connections from said shuttle changing mechanism whereby said latch is disabled during shuttle change.

In testimony whereof I have hereunto affixed my signature.
